UNITED STATES PATENT OFFICE.

FRANK D. WALDEN, OF JEFFERSONVILLE, INDIANA.

SHOE-UPPER-TURNING MACHINE.

SPECIFICATION forming part of Letters Patent No. 380,959, dated April 10, 1888.

Application filed January 30, 1888. Serial No. 262,455. (No model.)

To all whom it may concern:

Be it known that I, FRANK D. WALDEN, a citizen of the United States, residing at Jeffersonville, in the county of Clark and State of Indiana, have invented a new and useful Improvement in Shoe-Upper-Turning Machines, of which the following is a specification.

My invention relates to an improvement in shoe-upper-turning machines; and it consists in the peculiar construction and arrangement of devices that will be more fully set forth hereinafter, and particularly pointed out in the claims.

15 The accompanying drawing is a view in vertical perspective of a shoe-upper-turning machine embodying my improvements.

A represents a hollow pyramidal standard firmly secured to the frame of the machine X, formed in two sections fastened at any point, and so constructed as to contain an upright shaft, U, rounded and flattened at its upper end and having an offset pivot with a friction-roller at its lower end, and is allowed a free 20 up-and-down motion in the standard, in which suitable bearings are provided. To this shaft a reciprocating movement is communicated upward by a cam-wheel, N, on the horizontal shaft S, and downward by the coiled spring H, 25 which also serves to hold the offset pivot and its roller of the upright shaft onto the periphery of the cam-wheel.

G represents a presser firmly secured to the frame of the machine X, consisting of the 30 standard g, supporting the ears c c and terminating in the vertical surface T, and the presser-arm B, working in the ears c c of the standard g, and its presser-plate K, working against the corresponding surface T of the standard g, 35 and connecting at b with the connecting-rod D.

D represents a connecting-rod connecting the presser-arm B at b with a cam-lever, L, at l, and composed of two sections connected by the right and left screw-nut I. The cam-lever L, 40 connected with the connecting-rod, has its offset and friction-roller pressed upon the periphery of the cam-wheel M by means of the spring e.

S represents a shaft rotating in the hangers 45 V W, and carrying the two cam-wheels M N and the pulley-wheel J.

F represents a lifting device actuated by

an ordinary foot-lever (not shown) engaging the shaft U under the collar E, and so arranged as to disengage and keep disengaged the shaft 55 U from the cam-wheel N at will.

The mode of operation of the above-described machine is as follows: The shaft S is driven by suitable belting, and the power applied may result from steam or any suitable mechanism. 60 The cam-wheel N, working against the offset, and the coiled spring pushing against the collar, communicate to the shaft U a reciprocating movement up and down, its extent being governed by the shape and size of the wings of 65 the cam-wheel. Over the upper end of the upright workman slips a shoe-upper, as shown in dotted lines, and allows the shaft to penetrate each scallop in its turn, and to force it out to an extent permitted by the seam. While 70 this movement is in progress the parts of the upper turned by the foregoing process and movement are brought in succession between the jaws of the presser G, where they are flattened or beaded by a series of pressings or 75 beatings produced as follows: By means of the cam-wheel M and the spring e a reciprocating movement is imparted to the lever L, which in turn imparts, through the connecting-rod D, to the presser-arm B a rapid succession of movements against and from the stationary head and plate T of the standard g. Should the shoe-upper have a plain unscalloped edge, then the upright shaft U should be stationary, 80 and the shoe-upper should simply be drawn over it. The upright shaft is rendered stationary as follows: The long arm of the lever F is drawn down. By this means the shaft is lifted up and removed from engagement with the cam-wheel N. The pressing process is the same as 85 90 for the scalloped upper.

The force of the pressing or beading process is regulated by the length of the connecting-rod D, which is shortened or lengthened by the right and left screw-nut I.

95 By my machine I obtain these advantages over this process. The shoe-upper is not removed to another machine to be pressed, that operation in my machine being a continuation of the turning process.

The operation of pressing, owing to the rapidity of the movement of the presser, is more expeditious than the old process of hammering, while, owing to the uniformity of the beat-

ings of the presser-arm, there is no opportunity to break the leather at the seams by an unusually heavy blow—a mischance quite common to the old process.

5 I am aware that a machine exists wherein the turning of each scallop is accomplished by a corresponding depression of the treadle. My machine has the advantage over this of possessing mechanical means for turning the scallops without the intervention of the workman, and in greater rapidity of movement and uniformity of work.

10 I am also aware that there has been a turning device patented in which an up-and-down movement is given to a pusher working in an inclined projecting standard with a movable end, and is itself made in sections and actuated up and down in a slanting direction by a lever and foot-treadle. In this device, also, as foot 15 movement is no faster than hand movement, and as the device has no multiplying mechanism, it has little or no advantage over the old stationary finger in economy of time and labor. In my device, supposing steam-power to be 20 applied to the horizontal shaft, its large number of rotations would be converted into thrice the number of movements of the upright shaft, provided a three-winged cam-wheel be used.

25 Having thus described my invention, I claim 30 and desire to secure by Letters Patent—

1. A shoe-upper-turning machine in which devices for turning the edges of shoe-uppers and for pressing the same are combined, consisting of the standard A, attached to a suitable frame, X, the upright shaft U, to which a reciprocating movement up and down is given by the cam-wheel N and the coiled spring H, the presser G, likewise attached to the frame X, composed of the fixed standard g, and the presser-arm B, actuated by the cam-wheel M, and the lifting device F, all substantially as 35 described.

40 2. A shoe-upper-turning machine consisting of two standards, A and G, attached to the

frame X, the standard A constructed to admit freely the shaft U, and having a recess adapted to receive the coiled spring H, the standard G consisting of the arm g, supporting the presser-arm B, attached to it between the ears c c by a pin, the connecting-rod D, 45 the lever L, the shaft S, supporting the cam-wheels M and N and the pulley-wheel J, and the lifting device F, substantially as described.

50 3. In a shoe-upper-turning machine, the frame X, the standard A, the standard G, the connecting-rod D, connecting the presser-arm B with the lever L, formed in two sections, y and z, connected by the extension screw-nut I, the lifting device F, the cam-lever L, the shaft S, supporting the cam-wheel M, which actuates the presser-arm B through the lever L and the connecting-rod D, and the cam-wheel N, which actuates the upright shaft U and the pulley-wheel J.

55 4. In a shoe-upper-turning machine, the upright shaft U, rounded and flattened at its upper end to form a turning-iron, supporting the collar E and resting by means of an offset and friction-roller against the periphery of the cam-wheel N and working freely in the standard A, and supporting a coiled spring jammed between the collar E and the standard at P, the lifting device F, its lever catching the shaft under the collar and adapted to remove the shaft U from engagement with the cam-wheel 60 N, the presser-arm B, constructed to press the edge of a shoe-upper between its surface k and the head of the standard g, and the shaft holding the cam-wheels adapted to actuate the upright shaft U and the presser-arm B by means 65 substantially as described.

70 In testimony that I claim the foregoing as my own I have hereto affixed my signature in the presence of two witnesses.

FRANK D. WALDEN.
